ISOTOPE STORAGE CABINET

Felix R. Grat and Eugene L. Savettire, Lake Hiawatha,
and George E. Griffin, Cedar Grove, N.J., assignors
to Radiation Machinery Corporation

Filed July 1, 1969, Ser. No. 18,010

Term of patent 14 years

Int. Cl. D24—02

U.S. Cl. D16—2

FIG. 1

FIG. 2

FIG. 3

FIG. 4

FIG. 1 is a top plan view of an isotope storage cabinet showing our new design;

FIG. 2 is a front elevation view thereof;

FIG. 3 is a side elevation view thereof; and

FIG. 4 is a rear elevation view thereof.

We claim:

The ornamental design for an isotope storage cabinet, as shown and described.
